UNITED STATES PATENT OFFICE.

PETER F. LEON, OF NEW YORK, N. Y.

DESIGN FOR A MEDALLION, EMBLEM, BUTTON, OR SIMILAR ARTICLE.

Application filed March 28, 1921. Serial No. 456,482. Term of patent 14 years.

To all whom it may concern:

Be it known that I, PETER F. LEON, a subject of the Queen of Holland, residing at the city of New York, borough of Manhattan, in the county and State of New York, have invented a new, original, and ornamental Design for a Medallion, Emblem, Button, or Similar Article, of which the following is a specification, reference being had to the accompanying drawing, forming part thereof.

In said drawing the figure is a face view of a medallion, emblem, button or similar article, embodying or incorporating my said design.

I claim:

The ornamental design for a medallion, emblem, button, or similar article, as shown.

PETER F. LEON.
